UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 23,324, dated June 5, 1894.

Application filed April 26, 1894. Serial No. 509,156. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for Woven Fabric, of which the following is a specification, reference being had to the accompanying drawing.

The leading features of my design are represented and shown in the accompanying drawing, which is sufficient to enable others

skilled in the arts to make and use my invention.

Having as above fully described my invention, what I claim as new, and desire to secure by Letters Patent, is—

The design for a woven fabric, as shown in the accompanying drawing.

W. T. SMITH.
